UNITED STATES PATENT OFFICE.

EUCLID I. LA CHAPELLE, OF BROCKTON, MASSACHUSETTS.

MACHINE FOR OPERATING UPON SOLES.

Application filed December 1, 1925. Serial No. 72,535.

The present invention relates to machines for operating upon sole blanks, and more particularly to an automatic machine for simultaneously rounding, randing and inking the edge face of a channeled, welted McKay outsole prior to sole laying.

The object of the present invention is to produce an automatic machine in which the operation of trimming and the operation of 10 randing and the operation of inking the outsole edge face are simultaneously performed prior to the sole laying operation, as distinguished from the usual practice of performing these operations consecutively 15 and by manipulations after the outsole has been applied to the shoe, and to automatically perform these operations with best results, it is necessary to do so prior to sole laying, as herein proposed.

20 To the accomplishment of this object, and such others as may hereinafter appear, the features of the invention relate to certain devices, combination and arrangements of parts, hereinafter described and then set 25 forth broadly and in detail in the appended claims, which possess advantages which will be apparent to those skilled in the art.

The various features of the present invention will be best understood from an 30 inspection of the accompanying drawings, illustrating the best form of the invention at present devised, in which,

Figure 1 is a plan of the channeled face of a channeled, welted McKay outsole;

35 Fig. 2 is a plan of the welted face of the outsole;

Fig. 3 is a detail in sectional elevation of the outsole on the line 3—3, Fig. 2;

40 Fig. 4 is a plan of the support for the channeled, welted McKay outsole;

Fig. 5 is a plan of the outsole engaging face of the clamp for holding the outsole on the support;

45 Fig. 6 is a detail in elevation of a commercial Julian sole rounder having certain features of the present invention embodied therein;

Fig. 7 is a detail in plan showing the 50 operating tools engaged with the peripheral edge of the outsole;

Fig. 8 is a detail in sectional elevation

showing a channeled, welted McKay outsole in position between its support and clamp;

Fig. 9 is a detail in sectional elevation showing the supported and clamped outsole 55 with relation to the rounding and randing knife; and

Fig. 10 is a detail in sectional plan showing the means for inking the edge face of 60 the outsole.

The features of the present invention are embodied in an automatic sole-rounding machine which is provided with a pattern upon which the outsole rests, a clamp which presses upon the opposite plane surface of the outsole, holds it in position upon the pattern, and a knife which darts around the peripheral edge of the stationary pattern, cuts the outsole to the shape of the pattern. The machine to which my invention is applied is disclosed in the patent to Julian, No. 11,501, reissued July 2, 1895. The machine disclosed in the aforesaid patent has since been improved by the addition of a rebound mechanism which causes 65 the knife, after it has completed its traverse around the pattern, to first travel beyond the initial starting point and then to return and stop at about its initial starting position and such improvement is embodied, of course, in 70 the commercial Julian sole rounder.

75 Referring first to Figs. 1, 2 and 3 the work operated upon by the machine embodying the features of the present invention, comprises a channeled and welted McKay outsole 11 having one face thereof provided with a feather 12, a shoulder 13, and a shoulder lip 14 turned back and down upon the channeled face of the outsole. The other 80 face of the outsole is provided with a beveled welt 15 which is secured to the unchanneled face of the outsole by stitches 16 anchored on the welt 15 and feather 12, respectively, as in the usual practice after the McKay outsole has been died out from a 85 blank to the form of a shoe outsole preparatory to sole laying but, in connection with my present invention, without being moulded.

90 The McKay outsole is inserted into the machine illustrated in Fig. 6, which is a 95 regular Julian sole rounder such as disclosed

in the Julian patent hereinbefore referred to but modified to include the regular commercial rebound mechanism.

In order to support a channeled, welted 5 McKay outsole, the pattern 17 (Figs. 4 and 6) is provided with a beveled strip 18 arranged with one face in contact with the supporting face of the pattern. The opposite face 19 of the strip is beveled to 10 engage the feather 12 of the channeled, welted McKay outsole. One edge face, the face 20, of the strip 18, is arranged flush with the peripheral edge face 21 of the pattern. The opposite edge face, the face 22, 15 of the strip 18 is constructed and arranged to engage the shoulder 13 of the outsole. After mounting the outsole on the pattern 17, in the manner illustrated in Figs. 8 and 9, the clamp 23 (Figs. 5 and 6) is actuated 20 to cause its peripheral edge 23^a (Figs. 8 and 9) to engage the welt 15 and hold the outsole on the pattern 17.

The machine is then thrown into operation whereupon the knife 24 (Fig. 9) darts 25 around the pattern and simultaneously cuts the edge face of the outsole to the shape of the pattern and rands the peripheral top edge of the welt 15, or the top edge of the sole when the welt is omitted, and, as the 30 term "rand" implies, on a bevel extending over the marginal portion of the sole.

In order to simultaneously ink the face 35 of the outsole cut by the knife 24, the knife lever or support 25 (Fig. 7) carries a stud 26 upon which an arm 27 is pivoted. The arm 27 carries an ink reservoir 28 and a roll 29 mounted to rotate within the reservoir. The roll 29 is of felt and rotates within the reservoir with a portion of its peripheral 40 portion projecting therefrom in contact with the cut face of the outsole edge. In order to prevent leakage, the roll 29 is scraped by an edge 30 on the ink reservoir 28 and also by an edge 31 formed on a leaf spring 32 45 secured to an exterior wall of the reservoir 28. The roll 29 is held against the cut edge face of the outsole by a spring 33, coiled about the stud 26, one end of which is secured to the knife support 25 and the other end of which is engaged with the arm 27.

It is to be noted that, for positioning with absolute uniformity a given number of soles in the machine, nicks *a*, and *b*, are made at the sides of the heel portion (preferably by the dies used in conjunction with dieing out machines) and the pattern 17 is provided with sole holding projections *a'*, and *b'*, at the sides of the heel portion, which correspond as to location and form to the nicks 55 on the sole. Thus a given number of soles will be positively uniformly set relatively to the periphery of the pattern and sequentially may be applied uniformly to shoes at sole laying. Proceeding further towards obtaining uniformity at sole laying and facil-

tating the sole laying operation, the clamp 23 is provided at its inside ball portion and at its toe-end with projections *c*, and *d*, located at a substantial distance from its edge to thereby predetermine the sole extension 70 at sole laying by indentations on the welt strip on the sole (or on the sole proper when no welt strip is provided) so that the sole layer will readily lay the marked soles on the shoes with absolute uniformity. 75

It is to be further noted that, as hereinbefore stated, the outsoles are not moulded and, although a desirable feature in itself, moulding is not absolutely necessary, as the sole laying operation can include the laying 80 of the outsoles by the operator of the sole fastening machine employed in sole laying.

It is to be appreciated that although a 85 welted McKay outsole is herein shown, the invention and the application therefor is intended to cover and does cover the provision of any other type of outsole adapted to the practice of my invention and the appended claims are to be interpreted in this 90 broad sense.

What is claimed as new, is:

1. A machine for operating upon soles prior to sole laying having in combination sole-engaging means adapted to engage one 95 of the plane faces of the sole substantially in its entirety and additional sole-engaging means adapted to engage the opposite side face of the sole, substantially in its entirety, whereby the sole is held from displacement in the machine, edge cutting means, and edge liquid applying means simultaneously operative therewith for applying liquid to the freshly cut edge of the sole. 100

2. A machine for operating upon soles prior to sole laying having in combination sole-engaging means adapted to engage one of the plane faces of the sole substantially in its entirety and sole-engaging means adapted to engage the opposite side face of the sole, substantially in its entirety, whereby the sole is held from displacement in the machine, means for marking the sole preparatory to sole laying, means for randing the sole, and means for operating upon 110 the randed part of the sole. 115

3. A machine for operating upon soles prior to sole laying having in combination sole-engaging means adapted to engage one of the plane faces of the sole substantially in 120 its entirety and sole-engaging means adapted to engage the opposite side face of the sole, substantially in its entirety, whereby the sole is held from displacement in the machine, means for marking the sole preparatory to sole laying, means for randing the sole, and means for applying liquid material to the randed portion of the sole. 125

4. A machine for operating upon soles prior to sole laying having in combination 130

sole-engaging means adapted to engage one of the plane faces of the sole substantially in its entirety and sole-engaging means adapted to engage the opposite side face of the sole, substantially in its entirety, whereby the sole is held from displacement in the machine, edge trimming means for operating

upon the edge of the sole, and means for applying a material to the trimmed edge of the sole.

10

In testimony whereof I have signed my name to this specification.

EUCLID I. LA CHAPELLE.
